UNITED STATES PATENT OFFICE.

NICHOLAS A. BECKER, OF PITTSBURG, CALIFORNIA.

DESIGN FOR A RADIOLAERIAL.

Application filed August 1, 1927. Serial No. 22,966. Term of patent 14 years.

To all whom it may concern:

Be it known that I, NICHOLAS A. BECKER, a citizen of the United States, residing at 309 E. 9th Street, Pittsburg, county of Contra Costa, State of California, have invented a new, original, and ornamental Design for a Radiolaerial, of which the following is a specification, reference being had to the accompanying drawing, forming part thereof.

Figure 1 is a side elevation of the aerial, Figure 2 is a plan view of the top of the aerial.

I claim:

The ornamental design for a radiolaerial as shown.

NICHOLAS A. BECKER.
